UNITED STATES PATENT OFFICE

DONALD H. PARSONS, OF NOROTON, CONNECTICUT, ASSIGNOR TO McCALL COMPANY, OF NEW YORK, N. Y., A CORPORATION OF NEW YORK

BOOK

Application filed December 4, 1931. Serial No. 578,926.

This invention relates to the manufacture of books, and particularly to the manufacture of magazines or periodicals.

Magazines and periodicals are customarily bound either with a saddle wire stitch, a side wire stitch or a thread stitch depending upon the number of pages which it is desired to include in a single issue. All of the pages of a single issue are customarily bound together in a single volume, of course.

According to the present invention, I propose to divide the subject matter of any given issue of a periodical into a plurality of sections, which sections I propose to bind separately, preferably with a cover for each, and then to secure the separate sections together in such manner that the cover page of any given section may be exposed as the cover page of the combined book, according as the preference of the reader may dictate.

As a specific example, the subject matter of women's magazines may be divided easily into three classes, first matters of general interest, such as stories, poetry, editorials and the like, second, matters relating to home making, such as cooking, decorating, household economy, budgets and the like, and third, fashions, including dress making, millinery and the like.

The advantages from the publisher's point of view will be obvious. Since each section of the magazine would preferably have its own cover, the cover design may be of a character appropriate to the subject matter of the section, thus making for greater interest and increasing the value of the publications from an advertising standpoint. From the publisher's viewpoint also this invention should make the selling and securing of circulation materially easier with the obvious appeal to the prospective reader of having a plurality of magazines in one.

Furthermore, the advertising may be associated with the subject matter of the magazine to which it is most closely related. For

example, referring again to the example above, advertisements of automobiles, cosmetics, tooth paste, etc. might be placed in the general section, while advertisements of electric household appliances, foods, rugs and carpets might be placed in the home making section, while advertisements of shoes, hats, hosiery, etc. might be placed in the fashions section.

There are also advantages to the reader. The increase in the size of magazines has resulted in a greater difficulty on the part of the reader to handle the magazine conveniently. With this invention the reader is enabled to bring that section in which he is most interested on top, thus making for greater ease in handling and reading.

In addition the segregating of related editorial matter into a separate section within the magazine makes for greater editorial display with a resulting increase of reader interest. And further as editorial over-runs of each section may be contained within its section, there is a further increase in ease of handling and as such of reader interest.

From the publisher's viewpoint as well as of the advertiser's there is a distinct advantage in such a magazine by reason of the increased amount of preferred position, for instead of a single front and back cover with a single inside front and back cover, these positions may be increased by the number of covers for which there are sections. And from a publisher's standpoint this means that a greater volume of advertising may be carried at a greater profit as there is no necessity of facing such advertising with editorial matter which is a large item of publishing expense.

It is an object of the invention to provide a construction which will enable the above advantages to be realized.

Other objects and advantages of the invention will appear hereinafter.

A preferred embodiment of the invention

selected for purposes of illustration is shown in the accompanying drawings, in which,

Figure 1 is a plan view.

Figure 2 is an end view.

5 Figure 3 is a section on the line 3—3 of Figure 4.

Figure 4 is an enlarged side elevation.

10 Figure 5 is a section on the line 5—5 of Figure 3.

Figure 6 is a section showing one of the staples.

Figure 7 is a section on the line 7—7 of Figure 6.

15 Figure 8 is an end elevation showing the manner in which the sections may be rotated around the connecting member.

Referring to the drawings, the book illustrated may be termed a multiple book and comprises three sections, A B and C which 20 may be termed individual multi-leaved books and which are secured together in such manner that the position of the individual sections may be changed with respect to one another at the will of the reader. Each of the 25 sections is preferably provided with an outside cover 1 and may consist of any desired number of pages 2, and the individual sections are preferably separately hinged to a common hinge element, preferably formed 30 as an elongated member and of a character to lie entirely between the planes of the top and bottom faces of the multiple-book when the sections lie flat upon one another so as not to interfere with stacking and handling 35 during shipment, or be inconvenient in use.

In the preferred embodiment illustrated, the pages of each section are secured together by means of the ordinary saddle stitch 3 so that each of the sections forms a separately 40 bound unit.

45 In order to secure the individual sections or units together, it is desirable to provide a central securing element, together with means for securing each of the sections to the central element. For this purpose, in the present embodiment there are provided connecting members 4 in the form of short tubular members, placed adjacent the bound edges of the individual sections with their 50 axes paralleling the same and the individual sections may be conveniently secured thereto by means of staples 5 which closely resemble the ordinary saddle stitch. As shown, these 55 saddle-wire-like staples 5 also function to aid in retaining together the leaves of a leaf-section, folio, or signature through which they may be inserted (see Fig. 5) and may thus supplement or replace ordinary saddle stitches (see Fig. 6) in this connection, as indicated in Fig. 1, as well as to provide loops for hinging the individual sections to the common hinge element 4.

60 Referring to Figure 8, it will be seen that the individual sections may swing about the 65 connecting members 4 in order to bring any

desired section to the front of the assembled book. Thus in Figure 3, section A is on top, while in Figure 8 section A is being removed from the top position to the lowermost position, thus bringing section B on top. By swinging section B in the same manner, section C may be brought to the uppermost position. As will be observed, the relative positions of the sections may be changed as frequently as may be desired by the reader, the separate sections swinging freely on the central connecting member without danger of damaging the paper of which the sections are formed.

65 It will be understood that the invention may be variously modified and embodied within the scope of the subjoined claims.

I claim as my invention:

1. A multiple book consisting of a plurality of individual multileaved books, and 70 constructed to present any one of said individual books as the front section of the multiple book with said individual books lying flat on one another; said individual multileaved books being separately bound and 75 separately hinged at their bound edges to a common hinge element; said hinge element, when 80 said books lie flat on one another, lying entirely between the planes of the top and bottom faces of the multiple book; and said 85 hinge element providing for rotation of individual books thereabout from a flat position as the front section of the multiple book to a flat position as the back section thereof 90 and vice versa to present any one of said individual books as the front or back section 95 of said multiple book.

100 2. A multiple book according to claim 1 in which said hinge element comprises a tubular member, of a diameter less than the combined thickness of said individual books, placed adjacent the bound edges of said individual books, and with its axis paralleling 105 said bound edges, and in which said individual books are hinged thereto by individual loops extending through said tubular member and individually secured to the bound edges 110 of said individual books.

115 3. A multiple book according to claim 1 in which said hinge element comprises an elongated member, of a thickness less than the combined thickness of said individual books, placed adjacent the bound edges of said individual books, and with its length 120 paralleling said bound edges, and in which said individual books are separately hinged to said member by individual loops to provide for the independent swinging thereof about said member.

125 4. A multiple book according to claim 1 in which said hinge element comprises a member of a diameter less than the combined thickness of said individual books, placed adjacent the bound edges of said individual 130

books, and with its axis paralleling said bound edges, and in which said individual books each comprise a leaf section, folio, or signature at least partially bound by a saddle-
5 wire-like staple which also hinges said individual book to said member to provide for its rotation thereabout as set forth in claim 1.

In testimony whereof, I have signed my name to this specification this 3rd day of
10 December, 1931.

DONALD H. PARSONS.
